Wm. H. Reid.

UNITED STATES PATENT OFFICE.

JULIUS A. BROWN, OF PEEKSKILL, NEW YORK, ASSIGNOR TO ERNEST LOOMIS, OF PEEKSKILL, NEW YORK.

STYLUS MOUNTING FOR REPRODUCERS.

Application filed March 2, 1922. Serial No. 540,436.

To all whom it may concern:

Be it known that I, JULIUS A. BROWN, a native of Austria, and who has applied for citizenship of the United States of America, and a resident of Peekskill, in the county of Westchester and State of New York, have invented certain new and useful Improvements in Stylus Mountings for Reproducers, of which the following is a specification.

10 This invention has for its object to provide an improved resilient mounting for the stylus arm in a phonograph reproducer, in which the plate spring is extended in several directions to facilitate the vibration of the 15 parts; and which is provided with means for adjusting its tension, whereby the character of the vibration can be easily regulated.

In the accompanying drawings showing one embodiment of my invention, Figure 1 20 is a front elevation.

Fig. 2 is a side elevation, partly in section.

Fig. 3 is a detail view enlarged of certain parts.

Fig. 4 is a view showing the spring mounting parts separated in general order of assembly.

Fig. 5 is a plan view of certain parts.

The reproducer is of the usual form provided with a frame 1, and a diaphragm 2. 30 The stylus arm 3 is secured at one end to the diaphragm, and has its other end connected with a bracket 4 having a socket portion 5 for engaging the usual needle 6, secured therein by a set screw 7. These parts can be 35 of any desired construction.

For the mounting of the bracket 4, I provide a plate spring 8 having lateral extension or ears 9 and 10 at the extremities, shown as apertured, the spring being secured to the bracket 4, at its middle portion where it is bent to a curve.

The frame 1 is provided with a pair of ears 11 and 12, having bolts 13, 14, for engaging the apertured ears 9 and 10, whereby 45 the spring carrying the bracket and stylus arm is secured to the frame for vibration.

I also provide a bar 15 bowed at the middle portion, with its ends perforated to

engage the bolts 13 and 14, see Fig. 4. Preferably the blocks 16, 16, are placed between 50 this bar and the spring, and similar blocks are placed between the spring and the ears on the frame. When so assembled nuts are placed on these bolts, that will serve to lock the bar and the springs to the ears as shown.

55 It will be seen that the bar 15 is bowed to extend free from any of the other parts, and is engaged only at its end portions. This serves to strengthen the connection of the spring with the two ears on the frame.

60 The spring plate 8 has its upper end bent transversely as indicated at 17, which bent portion is cut away at 18 around the post or bracket 5 as shown. This will serve to give a certain amount of rigidity to the 65 spring, that will prevent an undue amount of vibration and strengthen its connection which will produce the desired vibration of the diaphragm. A device of this character 70 is found to produce very advantageous results, as the metallic sound frequently produced is taken away, and also the scratching or grating effect has been eliminated. The two bolts serve to mount the spring and its bar in a very rigid and secured manner on 75 the frame.

What I claim is:

1. A stylus mounting comprising a frame having a pair of ears at one side, a plate spring, a stylus arm secured to the spring 80 at its middle portion, the end portions of the spring being secured to said ears, the upper edge of the spring being extended transversely to the spring, but free from the arm.

2. A stylus mounting comprising a frame, 85 a plate spring secured at its ends to said frame, a flange projecting laterally from the free edge of said plate spring, and having an opening in the portion adjacent the plate spring, and a stylus arm secured to the 90 middle portion of the plate spring and projecting through the opening free from the flange.

Signed at Peekskill, N. Y., on February 24, 1922.

JULIUS A. BROWN.
